THREAD-TRIMMING MECHANISM FOR
SEWING MACHINES

Darwin G. Smith and Harold C. Faulkner, Bridgeport, Conn., assignors to The Singer Manufacturing Company, Elizabeth, N. J., a corporation of New Jersey

Application November 14, 1947, Serial No. 786,016

5 Claims. (112-252)

1

This invention relates to sewing machines and more particularly to thread-trimming mechanisms for machines of the "group-stitch" type, such as tacking machines, button-hole machines, eyelet machines, etc.

The invention aims to improve the thread-trimming and -nipping mechanism disclosed in the U. S. patent of A. R. Wood, No. 1,920,944, dated Aug. 1, 1933, so that after the thread has been cut and the beginning end of the thread nipped the work-clamps may be opened to release the work without causing any inadvertent shift of the nipping blade which would prematurely release the nipped end of the thread.

Another object of the invention is to provide actuating mechanism for the trimmer-blade constructed so that it will not encroach upon the work-clearance space beneath the work-clamp arms and will not interfere with the movement of the work-clamp into and out of work-clamping position.

With these and other objects in view, as will hereinafter appear, the invention consists in the thread-trimming and -nipping device described in connection with the accompanying drawings which illustrate a preferred embodiment of the invention and in which:

Fig. 1 is a right side elevational view of an eyelet machine embodying the invention, portions of the machine being broken away.

Fig. 2 is an enlarged top plan view of portions of the work-clamp and of the machine-frame, showing the actuating mechanism for imparting the required thread-trimming and -nipping motions to the trimmer.

Fig. 3 is a plan view of the feed-wheel, together with a portion of the mechanism for rapidly rotating the feed-wheel at the end of the sewing operation, and that part of the thread-cutter mechanism actuated by the feed-wheel reversing mechanism.

Fig. 4 is a top plan view of a portion of the right hand work-clamp section, showing the thread-trimming blade in set position preparatory to the retrimming of the beginning end of the needle-thread.

Fig. 5 represents a vertical section taken substantially along the line 5-5, Fig. 2, showing, in dotted lines, the position of the parts when the thread-trimming blade is open and, in full lines, the position of the parts when the thread-trimming blade is closed.

Fig. 6 is an enlarged vertical sectional view taken substantially along the line 6-6, Fig. 2.

2

Fig. 7 is an enlarged vertical sectional view taken substantially along the line 7-7, Fig. 2, showing the needle-thread just after it has been severed with the beginning end of the needle-thread nipped for the beginning of the subsequent stitching cycle.

In the preferred embodiment of the invention, the eyelet machine illustrated in the drawings comprises a frame including a bed 10 supporting a standard 11 of an overhanging bracket-arm 12 terminating in a head 13. Mounted in the head 13 is the usual reciprocatory needle-bar 14 carrying a needle 15 which, together with the regular under-thread mechanism mounted with 15 in the bed 10, constitutes the stitch-forming mechanism. This mechanism is adapted to be turned about a vertical axis to disperse the stitches about the eyelet. The stitch-forming mechanism is driven from the main sewing shaft 16 which derives its power from a continuously running belt-driven pulley 17. The period of operation of the stitch-forming mechanism is controlled by the usual start- and stop-motion device including the tilting stop-motion lever 18 which, when operated effects the coupling of the main-shaft 16 to the pulley 17.

As fully explained in the U. S. patent of E. B. Allen, No. 1,346,102, dated July 13, 1920, there is incorporated in the machine the usual eyelet-cutter shaft 19 which makes one revolution prior to sewing and then comes to rest, and a second auxiliary shaft 20 which is stationary during the operation of the shaft 19 and main-shaft 16 and makes one revolution after the sewing is completed, to perform certain desired operations after stitching, such as the opening of the work-clamp, and the rapid drive of the feed-wheel 21 to restore it to initial position. These shafts 19 and 20 are driven from a continuously running belt-pulley 17 through suitably controlled one-revolution clutch-devices, as fully explained in the above mentioned Allen Patent No. 1,346,102.

For a clear understanding of the present invention it will be sufficient to explain that, to rapidly drive the feed-cam 21, the second auxiliary shaft 20 is formed with a crank 23 which is connected by a pitman 24 to an arm 25 fulcrumed coaxially with the feed-wheel and pivotally carrying a pawl 26 which is urged by a spring 27 (Fig. 1) to ride on the periphery of the feed-cam and acts upon a tooth 28 on the feed-wheel during the single rotation of the crank 23; rapidly turning the feed-wheel at one sweep from 50 its position at the end of a sewing operation to

initial position ready to begin a new cycle of operations.

The work is adapted to be held in a work-clamp during the sewing operation. The work-clamp which is shown in the drawings forms the subject of pending application Serial No. 786,014, filed Nov. 14, 1947 in the name of H. C. Faulkner, and includes lower clamp-plates 29, 30 and opposed upper clamp-feet 31, 32. The clamp-feet are pivotally fastened by means of pivot-screws 33, 34 to the free ends of the arched clamp-arms 35 and 36, each of which is fulcrumed at its rear end on a hinge-pin 37 provided in a supporting bracket 38, only the bracket for the clamp-arm 35 being shown in the drawings. The clamp-foot 31 is yieldingly held against the work, when the work-clamp is closed, by a coil-spring 39 which is interposed between the arm 35 and a thumb-nut 40 threaded on a pull-rod 41. As fully shown and described in the pending application above referred to, there is provided suitable toggle mechanism connected with the pull-rod 41 for effecting the closing and opening of the work-clamp. The clamp-arms 35, 36 are appreciably arched and the fulcrum supports for said arms are disposed considerably back from the feet 31, 32 in order to provide ample work-clearance space beneath the arms.

The needle-thread trimming and -nipping mechanism now to be described comprises a trimmer-blade 42 and an overlying nipper-blade 43 (Figs. 4, 5 and 7), the shanks of which are secured to the lower end of the usual vertical rock-shaft 44 journaled in the clamp-foot 31. This construction is substantially the same as that disclosed in the U. S. patent of E. B. Allen, No. 885,310, dated April 21, 1908. The thread-trimming and nipping blades 42 and 43 are adapted to operate in a horizontal slot defined between a section 45 of the clamp-foot 31 (Figs. 6 and 7) and the surface of a hardened detachable section 46 secured to the clamp-foot 31. The nipper-blade 43 cooperates with the section 45 as shown in Fig. 7 to hold the beginning end of the thread during the sewing of the first portion of the eyelet. The trimmer-blade 42 has a sharpened edge which cooperates with an edge on the detachable section 46 in severing the needle-thread.

The trimmer-blade carrying rock-shaft 44 has fixed on its upper end a rock-arm 47 connected by a link 48 to a rock-lever 49 freely pivoted on a stud 50 threaded into the clamp-foot 31. Depending from the rock-lever 49 is a ball-stud 51 embraced by the socketed front end of an actuating link 52 arched in substantial conformity with the clamp-arm 35 (Fig. 1) and connected at its rear end to the upper end of a trimmer-opening lever 53 pivoted intermediate its ends on a stud 54 threaded into the supporting bracket 38. Rising from the upper end of the trimmer-opening lever 53 is a projection 55 to which is attached one end of a coil-spring 56 connected at its other end to an ear 57 secured to the clamp-arm 35, the coil-spring acting to bias the trimmer-opening lever 53 into trimmer-blade closed position determined by a buffer pad 58 secured to the trimmer-opening lever 53 contacting an upstanding stop 59 provided on the clamp-arm 35. As will be seen in Figs. 2, 6 and 7, when the trimmer- and nipper-blades 42 and 43 are in closed position, the center of the ball on the ball-stud 51 is disposed in alignment with the longitudinal axis of the pivot-screw 33. It will be appreciated that while this aligned position of the ball-and-socket joint of the link 52 with the piv-

ot-screw 33 is maintained, any tilting of the clamp-foot 31 about the axis of the pivot-screw 33 while the work-clamp is opened will not cause the trimmer- and nipper-blades 42 and 43 to shift in the slot in the clamp-foot 31. Obviously, since no accidental shift in the blade 43 occurs the beginning end of the thread is held securely regardless of whether the clamp-foot 31 is tilted about the pivot-screw 33 during the insertion or removal of work from the opened work-clamp.

The thread-trimming and -nipping blades are adapted to be operated twice for each complete stitching cycle, once before the sewing is completed to retrim the beginning end of the needle-thread, the operation being performed preferably after the sewing has progressed to the point where the beginning end cannot be sewed in or bound down by the stitching, and a second time after the sewing is completed to cut the needle-thread close to the work and hold the beginning end of the needle-thread for the beginning of the next sewing operation. A thread-trimming mechanism having substantially the same sequence of operations is disclosed, for example, in the U. S. patent of A. R. Wood, No. 1,839,823, issued Jan. 5, 1932. In the present case, the first or retrim operation is performed by means actuated by the feed-cam 21. This means preferably comprises a vertically disposed rock-shaft 60 journaled in the bed 10 and having attached to its lower end an arm 61 having its inner end underlying the feed-cam and disposed to be engaged by a retrim-cam 62 attached to the under side of the feed-cam 21. Secured to the upper end of the rock-shaft 60 is a rock-lever 63 provided at its outer end with a slot 64 disposed to receive a screw 65 threaded into a push-lever 66 fulcrumed at one end on a pivot-stud 67. The free end of the push-lever 66 is arranged to swing into engagement with the lower end of the trimmer-opening lever 53. A spring 68 bears against the push-lever 66 and urges it into an inoperative position determined by a stop-pin 69. From the above description considered in connection with Figs. 2 and 4, it will be understood that as the feed-cam 21 turns in the direction of the arrow in Fig. 2, the retrim-cam 62 contacts the free end of the arm 61 which swings it in a counterclockwise direction, transmitting to the push-lever 66, through the rock-shaft 60 and rock-lever 63, movement in a counterclockwise direction also. This movement of the push-lever 66 turns the trimmer-opening lever 53 from the full line position in Fig. 5 to the dotted line position. This turning of the trimmer-opening lever 53 gradually moves the trimmer- and nipper-blades 42 and 43 into an open position, shown in Fig. 4. In swinging from closed or thread-nipping position to open position, the beginning end of the needle-thread is released and the trimmer-blade is set for its retrim stroke. As the feed-cam 21 continues to turn, the retrim-cam 62 advances to a point where its drop-off passes the end of the arm 61 and when this occurs the coil-spring 56 snaps the link 52 in a direction to close the trimmer-blade 42 upon and retrim the beginning end of the needle-thread close to the work. The spring 68 acts simultaneously with the coil-spring 56 in returning the push-lever 66 and its associated connections to their inoperative position.

To provide for reopening or resetting the trimmer-blade 42 preparatory to the trimming of the finishing end of the needle-thread (Fig. 7) and nipping the beginning end of the needle-thread 75 for the beginning of the next sewing operation,

we have provided a second means actuated by the single rotation of the auxiliary shaft 20 for operating the rock-shaft 60. This means preferably comprises a rock-arm 70 (Figs. 1 and 5) secured to the rock-shaft 60 and extending substantially horizontally immediately above the level of the feed-cam 21. At its free end the rock-arm 70 is formed with a downturned lip 71 providing on its inner face a straight cam-wall 72 extending in a direction inclined to and extending across the path of travel of the feed-cam turning pawl 26. The pawl 26 is provided with an upstanding pin 73 which is disposed so that, as the pawl 26 is actuated by the pitman 24 to effect the rapid turning of the feed-cam 21 after the stitching operation is completed, the pin 73 will strike the cam-wall 72 and swing the rock-arm 70 in a counter-clockwise direction and into the position shown in Fig. 3. With the parts in the position shown in Fig. 3, the trimmer- and nipper-blades 42, 43 are open or reset. As the pawl 26 continues in its feed-cam turning stroke, the pin 73 travels beyond the end of the rock-arm 70, permitting the spring 56 to snap the trimmer- and nipper-blades 42, 43 into closed position, whereby the thread is cut and the beginning end nipped (Fig. 7). The spring 68 returns the rock-arm 70 and its associated connections to the position illustrated in Fig. 2. When the crank 23 on the auxiliary shaft 20 travels through the second half of its single revolution, the pawl 26 is returned to its initial position in readiness for its operation at the end of the next stitching cycle. During the return stroke of the pawl 26 to its initial position the pin 73 on said pawl strikes the outside face of the downturned lip 71, causing the pawl 26 to turn in opposition to the spring 27 on its pivotal connection with the arm 25, the spring 27 biasing the pawl back so that its toe rests on the periphery of the feed-cam 21 after the pawl passes the back end of the downturned lip 71.

It will be appreciated from the foregoing that we have invented a needle-thread trimmer and nipping device constructed so that the nipper-blade is not accidentally shifted and the beginning thread-end released by the tilting of the work-clamping foot on its pivotal support during the insertion or removal of work or during the traversing of any unevenness in the material due to cross-seams or the like. Moreover, the actuating mechanism for the trimmer and nipping device is arranged so that ample clearance space is provided beneath the work-clamping feet to permit convenient manipulation of the work and to permit the placing of the stitched pattern back from the edge of the work. Also the actuating connections are designed so that they will not interfere with the movement of the work-clamp into and out of work-cutting position, and the position of the pivot 54 of the trimmer-opening lever 53 relative to the hinge pin 37 of the clamp-arm 35 is such that during the opening and closing of the work-clamp the buffer pad 58 slides up and down on the face of the stop-lug 59 in a direction substantially normal to the axis of the link 52. Thus, no endwise movement is imparted to the link 52 during the opening and closing of the work-clamp and consequently the trimmer- and nipper-blade is not disturbed.

Having thus set forth the nature of the invention, what we claim herein is:

1. A group-stitch sewing machine having a work-clamp provided with an upper clamp-foot pivotally mounted for tilting movement about a fulcrum-axis, a thread-trimmer and -nipper de-

- vice carried by said upper clamp-foot, and actuating mechanism for operating said thread-trimmer and -nipper device; said mechanism including a pair of elements carried by said work-clamp and a ball-and-socket connection between said elements with the center of the ball disposed in alignment with the fulcrum-axis of said clamp-foot when said thread-trimmer and -nipper device is closed.
- 10 2. A group-stitch sewing machine having a work-clamp provided with an upper clamp-arm, a bracket to which said clamp-arm is pivoted, a clamp-foot mounted on one end of said clamp-arm for tilting movement about a fulcrum-axis, a thread-trimmer and -nipper device carried by said clamp-foot, and actuating mechanism for operating said thread-trimmer and -nipper device, said actuating mechanism including a rock-lever pivoted on said clamp-foot, a trimmer-opening lever fulcrumed on said bracket, a link connected at one end to said rock-lever and at its other end to said trimmer-opening lever, the point of connection between said link and rock-lever being in alignment with the fulcrum-axis of the clamp-foot when said thread-trimmer and -nipper device is closed, and means for operating said trimmer-opening lever.
- 15 3. A group-stitch sewing machine having a work-clamp provided with an arched upper clamp-arm, a bracket to which one end of said clamp-arm is pivoted, a clamp-foot mounted on the other end of said clamp-arm, a thread-trimmer and -nipper device carried by said clamp-foot, and actuating mechanism for operating said thread-trimmer and -nipper device, said actuating mechanism including a rock-lever pivoted on said clamp-foot and operatively associated with said thread-trimmer and -nipper device, a trimmer-opening lever pivoted on said bracket adjacent the pivotal support of said clamp-arm, a link shaped to conform substantially with the arched clamp-arm and connecting said trimmer-opening lever to said rock-lever, and automatically controlled means for operating said trimmer-opening lever.
- 20 4. A group-stitch sewing machine having a stitch-forming mechanism, a feed-cam for effecting the distribution of stitches in a given pattern, feed-cam rapid-turning means for returning the feed-cam to its initial position after the stitching is completed, a thread-trimmer and -nipper device, and means for actuating said device twice for each complete stitching cycle, said means including a rock-shaft, means operatively connecting said rock-shaft to said thread-trimmer and -nipper device, a reset cam on said feed-cam, a rock-arm secured on said rock-shaft and disposed for engagement by said reset cam to effect one of the operations of said thread-trimmer and -nipper device, and a second rock-arm secured to said rock-shaft and arranged for engagement by said feed-cam rapid-turning means for effecting the other operation of said thread-trimmer and -nipper device.
- 25 5. A group-stitch sewing machine having a work-clamp provided with an upper clamp-arm, a clamp-foot mounted on said clamp-arm for tilting movement about a fulcrum-axis, a thread-trimmer and -nipper device carried by said clamp-foot, and actuating mechanism for operating said thread-trimmer and -nipper device, said actuating mechanism including a trimmer-carrying rock-shaft, a rock-arm secured to said rock-shaft, a rock-lever pivoted on said clamp-75 foot, a link connecting said rock-arm to said

rock-lever, a second link connected to said rock-lever at a point in alinement with the fulcrum-axis of said clamp-foot when said thread-trimmer and -nipper device is in closed position, and operating mechanism connected to said second link.
